UNITED STATES PATENT OFFICE.

JOHN D. FLANNAGAN, OF KOSSE, TEXAS, ASSIGNOR OF ONE-HALF TO B. V. SOWDERS, OF SAME PLACE.

FEED-GOVERNOR FOR COTTON-GINS.

SPECIFICATION forming part of Letters Patent No. 279,867, dated June 12, 1883.

Application filed October 25, 1882. (No model.)

To all whom it may concern:

Be it known that I, JOHN D. FLANNAGAN, a citizen of the United States, residing at Kosse, in the county of Limestone and State of Texas, have invented a new and Improved Feed-Governor for Cotton-Gins, of which the following is a specification.

My invention relates to that class of cotton-gins in which circular saws separate the cotton from the seed, both being fed by suitable mechanism into the roll-box. When cotton is fed upon the saws faster than they gin it, the accumulation is caused to roll over and over by the action of the saws, and when this roll increases beyond the capacity of the roll-box the gin cannot operate; and the object of my invention is to provide means whereby the rate of feeding will be automatically decreased when the cotton is fed into the roll-box faster than it is being ginned, and whereby the feed will be finally stopped when the roll increases to a certain limit, and will be again started when the roll is reduced to a size previously fixed upon, and will be actuated to feed faster as the roll decreases in size.

To this end my invention consists in the construction and combination of parts hereinafter fully described and claimed, reference being had to the accompanying drawings, in which—

Figure 1 is a longitudinal vertical section of a portion of a cotton-gin showing my invention. Fig. 2 is a side elevation of the same; and Fig. 3 is a transverse vertical section, partly in elevation, showing a portion of the feeding mechanism.

A represents the saws operating between the ribs *a* upon the roll of cotton *B*. *D* represents the seed-board; *E*, the breast; *F*, the feeding-apron, revolving as a band around the two apron-rollers *f*; and *G* is the feed-roller, which takes the cotton from the apron *F* and drops it into the roll-box *b*.

Thus far the description is of a common cotton-gin, in which *C* represents the head-board, usually made as a rigid portion of the cylindrical wall of the roll-box *b*; but I hinge this head-board, which is a slat extending across the roll-box, forming the side of the gin-mouth next to or over the saws at *c*, to the body of the gin, to swing vertically, so that its free edge will rest upon the roll *B*. As this roll

increases in bulk the head-board rises, and when the roll diminishes the head-board falls. To the head-board I attach a lever-arm, *d*, extending back some distance beyond the fulcrum, which is the hinge *c*, to communicate with pawl *j* by means of a cross-lever, *e*, fulcrumed at *g*, and a vertical lifting-bar, *h*, which carries a roller, *i*, to operate upon the pawl *j* to raise and lower the same, so that said pawl *j*, which is hung upon a lever, *k*, may be engaged with or disengaged from the ratchet-wheel *n*. Said pawl *j* is operated by means of the pitman *l*, connecting said lever *k* with a crank, *m*, on the shaft of feed-roller *G*, to work the ratchet-wheel *n*, which is secured to the shaft of one of the feed-belt rolls, *f*, thus actuating said belt to feed the cotton to the roller *G*, which carries it over and drops it into the roll-box. The lever *k* is provided with several holes, *o*, in which to insert the pin connecting it with the pitman *l* for the purpose of increasing or decreasing the angle of motion of said lever in order that it may draw its pawl *j* back far enough to engage one or more teeth of the ratchet-wheel *n*, and thus limit the extreme rate of feed, for, however the height of the roller *i* may vary, the pawl *j* cannot move a tooth more than it is itself moved by the lever *k*. To the lower end of the bar *h* is attached a spring, *p*, to which is hung a cord, *q*, that is wound upon a pin, *r*, to which it is secured. This pin is tapered at one end to be driven into a hole in the side of the gin, and is provided with a thumb-screw head by means of which the cord *q* may be wound on it and the spring tightened. This spring acts to hold the bar *h* down, and by means of the levers *e* and *d* to also hold the head-board down, and when the governor and bar are at their lowest point the pawl *j* is allowed to take the greatest number of teeth of ratchet *n*; but when they are at their highest point said pawl rides upon the roller *i* and takes no teeth. Between these two extremes there is a medium range, which is made to correspond to the usual capacity of the gin by means of the adjusting-holes *o* in lever *k*, the adjustable fulcrum *g*, and the adjusting-holes *s* in bar *h*. If lever *e* be placed in a lower hole *s*, the head-board *C* will be carried lower, and will be operated by a smaller roll of cotton *B*, to effect the feed relative thereto, and if lever

e be placed in a higher hole *s* a larger roll will be made the standard to regulate the feed. The fulerum *g* is a bracket provided with a long slot in its base, by means of which it may be set along lever *e* and fastened to the framework by a bolt in said slot. By this means a given amount of motion of the head-board *C* may be controlled to give more or less motion to the bar *h*, and by means of the different holes *s* in said bar the field of motion may be raised or lowered. A spring-scale, *t*, may be interposed between the spring *p* and the cord *q* to register the amount of pressure on the governor.

15 Thus by the various devices described I am able to regulate the feed of cotton to a gin to the exact rate at which the machine is able to gin it under all the varying circumstances of sharp and dull saws, wet and dry, dirty and 20 clean cotton, for the action of my governor is dependent directly upon the size of the roll of cotton to regulate its rate of feeding. If the roll gets small, the saws are ginning faster than cotton is supplied, and immediately the feed 25 increases. If the roll gets large, the saws are hampered and do not gin all the cotton that is fed in, and the rate of feed is checked automatically, thus utilizing the greatest possible capacity of the gin.

30 I am aware that cotton-gins are in use which operate the feeding mechanism by the varying size of the roll acting on a movable breast which transmits its motion to the regulator of the feeding device. Those gins act on the cotton that is fed into the roll-box before it gets 35 around to the saws, and every succeeding bunch of cotton and the spaces between cause the breast to fluctuate unnecessarily, because the saws would naturally use the time between lumps in ginning the lumps, thus maintaining 40 a general equilibrium were it not for said fluctuations of the breast changing the feed. My governor is acted on by the roll in that arc of its cylinder between the saws and the feed- 45 opening after the saws have acted on the roll. Thus if the saws gin the cotton as fast as it is fed in, whether in lumps or otherwise, the remainder of the roll does not vary and my governor does not vary; but whenever the roll 50 varies in size after being acted on by the saws, then the saws are not ginning at the same rate that the cotton is being fed in, and the rate of feeding should be gradually varied to meet the emergency. This my governor does effectively.

55 It is not necessary that my head-board should be at the inlet of the gin, though there is where I place it for convenience in adapting it to gins already in use, and I would recommend that in making new gins this head-board *C* be 60 placed as shown; but in order to conform to

my invention it must be placed somewhere in the roll-box to be acted on by the roll after the saws have acted on it and before the fresh cotton comes in contact with it. The action of the saws is to drive the roll up into this arch 65 of the box—that is, the arch above the saws, and between them and the mouth of the gin into which the cotton is fed, and it rests against the breast only when about to clog.

What I claim as my invention is—

70

1. The combination, with the roll-box of a cotton-gin, of a head-board fulerumed to the box to swing within its arch to rest upon the roll in that arc of its circumference which has passed the saws before new cotton is taken 75 onto said roll, feeding mechanism, and means for transmitting the motion of said head-board, caused by the increasing or diminishing of said roll to the feeding mechanism, whereby the feed of cotton into the gin will be accelerated when the roll diminishes, and retarded when the roll increases beyond a fixed size, as specified.

2. The combination, with the roll-box *b* and saws *A* of a cotton-gin, of the head-board *C*, 85 hinged at *c*, and provided with the arm *d*, the lever *e*, the adjustable fulerum *g*, the bar *h*, the roller *i*, the pawl *j*, and its ratchet *n*, substantially as specified.

3. The combination, with the hinged head-board *C*, levers *d* and *e*, bar *h*, roller *i*, and feeding-pawl *j*, of the fulerum *g*, provided with a slot and a bolt therein, whereby the position of the fulerum may be changed to vary the leverage, as specified.

95

4. The combination, with the hinged head-board *C*, levers *d* and *e*, and the adjustable fulerum *g*, of the bar *h*, having several adjusting-holes, *s*, the roller *i*, pivoted thereon, and the feeding-pawl *j*, as specified.

100

5. The combination, with the hinged head-board *C*, levers *d* and *e*, fulerum *g*, bar *h*, roller *i*, and feeding-pawl *j*, of the spring *p*, as and for the purpose specified.

6. The combination, with the bar *h* and 105 spring *p*, of the tapering pin *r*, provided with a thumb-screw head, cord *q*, and means of connecting it with spring *p*, as specified.

7. The combination, with the crank *m* on the shaft of roller *G*, the pitman *l*, the ratchet-wheel *n* upon the shaft of one of the apron-rollers *f*, the pawl *j*, engaging said wheel, and the lever *k*, provided with several adjusting-holes, *o*, and the connecting-pin of the rod *l*, substantially as specified.
